O'Shaughnessy

UNITED STATES PATENT OFFICE.

HERMAN F. LEICHTFUSS, OF MILWAUKEE, WISCONSIN.

WATER SEAL FOR CONTAINERS.

Application filed November 9, 1922. Serial No. 599,797.

To all whom it may concern:

Be it known that I, HERMAN F. LEICHTFUSS, a citizen of the United States, and resident of Milwaukee, in the county of

5 Milwaukee and State of Wisconsin, have invented certain new and useful Improvements in Water Seals for Containers; and I do hereby declare that the following is a full, clear, and exact description thereof.

10 The invention relates to a water seal for containers. It comprises in one modification, a basin, a pipe extending through an opening in the bottom thereof, a cork enveloping the pipe below the basin, a valve 15 at the top of the pipe adapted to prevent air from flowing downwardly through the pipe, and a bottle enveloping the valve and the upper portion of the pipe and having its mouth resting upon the bottom of the 20 basin.

The primary object of the invention is the provision of a water seal adapted to permit the free escape of gas. The valve is light in weight so that a small amount 25 of pressure is operative to cause a release of gas. On the escape of the gas or on the production of a vacuum in the container, the valve is operative to check the inflow of air to preserve the contents of the container 30 in an uncontaminated condition. The device is reliable. There is substantially no possibility of leakage.

An object of the invention is the provision of a small unit which can be readily 35 affixed to the containers and is adapted to be fitted to openings in various types of receptacles, such as bottles and casks. A cork is provided which may be pushed into an opening having a tight closure.

40 A further object of the invention is the provision of a construction which is cheap, economical, inexpensive to manufacture, made of a minimum number of parts, and of especial simplicity.

45 With the above and other objects in view, which will appear as the description proceeds, the invention resides in the novel construction, combination and arrangement of parts, substantially as hereinafter described and more particularly defined by the appended claims, it being understood that while several modifications of the device are disclosed, the invention is capable of being modified further to a great extent, and applicant does not limit himself to the precise construction shown, but de-

sires to embrace a substantial range of equivalents within the scope of the appended claims.

In the accompanying drawing is illustrated several modifications, so far devised for the practical application of the principles thereof, and in which:—

Figure 1 is a side elevation of an embodiment of the invention. 65

Figure 2 is a similar elevation of another modification.

Figure 3 is an enlarged view of some of the parts shown in Figure 2 designed to bring out the valve operation. 70

Figure 4 is a side elevation of a third modification.

Figure 5 is a side elevation of a fourth modification, and

Figure 6 is an enlarged view of parts 75 shown in Figure 5.

In all of the figures parts are broken away to better show the construction.

In the modification shown in Figure 1, a basin 10 has a pipe 11 extending through 80 an opening in the bottom thereof, the pipe being rigidly connected to the basin by solder, or many other suitable ways. The pipe extends upwardly to point 12, being gradually bowed over and extending downwardly, having its terminus adjacent the bottom of the basin, which may be filled with water or any desired kind of liquid. A cork 13 envelops the pipe below the basin and contacts with the bottom of 90 the basin. The pipe is adapted to be inserted into the neck 14 of a bottle but is not limited for use in this specific connection, being adapted for application to openings in various types of containers. 95

The formation of gas in the container, which may occur in fermentative processes, such as wine making, results in the escape of the fluid upwardly through the pipe, the gas bubbling up through the water in basin 10. 100 The escaping gas overcomes a minor pressure of water in the basin 10, but the height of point 12 is such that on the cessation of pressure by the gases, there is no possibility of return of water or air through the pipe. 105 Consequently, the contents of the bottle are preserved uncontaminated and a continuous, uninterrupted fermentative process results, an effective sealing of the contents occurring.

In the modification shown in Figure 2, a 110 flat valve 15 is located at the upper terminus of the pipe, an elongated stem 16 extending

from the valve into the end of the pipe. The valve is adapted normally to rest on the bottom of the basin and therefore offers no resistance to the escape of gases. When 5 part of the contents of the bottle is withdrawn, or when the bottle is cool so as to create a suction therein, there is a tendency for the liquid in the basin to return through the pipe. This lifts valve 15, 10 checking the inflow of the water and protecting the contents of the bottle. The short spacing of valve 15 from the mouth of the pipe is such that the inflow of water readily catches and lifts the valve to closing position. 15

In the modifications shown in Figures 4, 5, and 6, the pipe is substantially straight, there being no curvature of the upper part thereof. A bottle 17 envelops the upper 20 portion of the pipe, its neck resting on the bottom of the basin. The bottle is very light in weight so that but a small pressure produced by the gases rising in the pipe and descending in the bottle is sufficient to tilt 25 the bottle slightly, whereby an escape of the gas into the basin results. The bottle operates to prevent an inflow of water under the action of suction produced in the bottle or casks as the neck of the bottle rests on 30 the bottom of the basin and effects a seal which is accentuated by the suction. To make doubly sure the impossibility of sucking in water and air below the bottle, a flat valve 18 is provided resting on the upper 35 end of the pipe and having a stem 19 extending downwardly into the pipe. The valve is lifted by the rising gases, but suction serves only to seat it more tightly on the end of the pipe, making an effective

closure and preventing the contamination 40 of the contents of the bottle or of the container. The flat portion 20 of the bottle is spaced slightly above the valve.

The pipe may be made of any desired material, copper being satisfactory, and the 45 basin is preferably made of sheet metal. It is apparent that cork 13 may be inserted into the opening of any type of container. Where the opening is very large, a large 50 cork may be used. An effective seal results, preventing escape of gases or inflow of air. The unit is small, made up of a few parts, simple, and of a less cost of production.

Claims:—

1. The combination of a basin, a pipe 55 extending through an opening in the bottom thereof, a stopper enveloping said pipe below said bottle, means for conducting gases escaping through said pipe downwardly to the bottom of said basin, said 60 basin being adapted to contain water, and a valve cooperating with said means for preventing the return of fluid through said pipe.

2. The combination of a basin adapted to 65 contain a liquid, a pipe extending through the bottom thereof, a stopper enveloping said pipe, a flat valve resting upon the top of said pipe, a stem on said valve extending into said pipe, and a movable member 70 enveloping said pipe and valve and resting on the bottom of said basin, said member having a closed upper end.

In testimony that I claim the foregoing I have hereunto set my hand at Milwaukee, 75 in the county of Milwaukee and State of Wisconsin.

HERMAN F. LEICHTFUSS.
